UNITED STATES PATENT OFFICE.

THOMAS S. HASKELL, OF SPRINGFIELD, MASSACHUSETTS.

PAN OR STOVE-COVER LIFTER.

SPECIFICATION forming part of Letters Patent No. 279,153, dated June 12, 1883.

Application filed November 24, 1882. (No model.)

To all whom it may concern:

Be it known that I, THOMAS S. HASKELL, a citizen of the United States, residing at Springfield, in the county of Hampden and State of Massachusetts, have invented new and useful Improvements in Pan or Stove-Cover Lifters, of which the following is a specification.

This invention relates to a combined dish and stove-cover lifter, and is fully set forth in the accompanying drawings and following description.

In the drawings, Figure I is a top view of my improved tool. Fig. II is a side elevation of the invention employed as a pan or dish lifter. Fig. III is the same view of the device used as a stove-cover lifter, and Fig. IV is a detail plan view of one jaw.

B is a jaw prolonged from the handle H and rigid therewith, and provided upon its jaw-surface with transverse grooves or corrugations b. Hinged upon the piece B at c is the opposing jaw-piece D, having upon its jaw-surface the transverse groove d. The part D is extended upon the other side of the hinge c to form a hook, C, which, extending below the jaw B, terminates in an end, h, adapted to catch in the hook-opening of a stove-cover, and sufficiently in advance of the jaws B D to approximate, as seen in Fig. II, to the inclined 30 side of a pan, W, grasped between said jaws. Also, prolonged from the jaw D, to be in convenient reach of the hand grasping the handle H, is the thumb-piece I.

In a tool so constructed a pan or dish grasped upon its rim by the jaws D B bears through its side upon the longer arm or hook C, to automatically cause the jaws to hold with a force proportionate to the weight of the pan, so that the pan, no matter what its weight, is by the

hook C and jaws D B firmly held, to be conveniently moved. One of the grooves b in jaw B and groove d in jaw D adapt themselves to the wire rim of a certain class of pan, as shown in the drawings, and these grooves in the opposing jaw-surfaces sufficiently roughen them 45 for an effective grip upon all classes of cooking utensils. To grasp a pan, the jaws are opened by means of the thumb-piece I, and when the rim is between said jaws the handle H is slightly lowered to bring the hook end h 50 against the side of the pan to complete the adjustment of the tool for use.

When the hook C is used to lift a stove-cover, the jaw D, bearing against jaw B, causes the hook C to be rigid with handle H.

Now, having described my invention, what I claim is—

1. The within-described dish or pan lifter, consisting of the handle H and rigid jaw B, in combination with the jaw D, hinged thereto to swing above jaw B, and provided with the extended bearing-arm C to swing below the same, substantially as shown and described.

2. The combination, with the jaws B D and arms C, arranged and operating as shown and described, of the corresponding transverse grooves, d and b, in the jaw-surfaces, adapting the jaws to inclose a wire rim, as set forth.

3. The combination, with the handle H, jaw B, and arm C, constructed and arranged substantially as shown, of the end h, adapted to form a stove-cover hook.

THOMAS S. HASKELL.
